**COMBINED TELEVISION VIEWER AND
CHAIR SHELL UNIT**

**Lyle A. Atkinson, Granger, Utah, assignor to Midwest
International, Granger, Utah**

Filed May 12, 1971, Ser. No. 142,847

Term of patent 14 years

Int. Cl. D6—01

U.S. Cl. D6—42

FIG. 1

FIG. 2

FIG. 3

FIG. 4

FIG. 5

FIG. 6

FIG. 7

FIG. 8

FIG. 1 shows a unit of the claimed design in elevation from the front;

FIG. 2 is a top plan view, to the same scale, of the unit shown in FIG. 1;

FIG. 3 is a bottom plan view, to the same scale, of the unit shown in FIG. 1;

FIG. 4 is a view in elevation, looking from the left, to the same scale, of the unit shown in FIG. 1;

FIG. 5 is a view in elevation, looking from the right, to the same scale, of the unit shown in FIG. 1;

FIG. 6 is a view in elevation, looking from the back, to the same scale, of the unit shown in FIG. 1;

FIG. 7 is a view in cross section, taken along the vertical plane intersecting the line 7-7 of FIG. 2, looking in the direction indicated by the arrows;

FIG. 8 is a view in cross section, taken along the vertical plane intersecting the line 8-8 of FIG. 2, looking in the direction indicated by the arrows.

I claim:

The ornamental design for a combined television viewer and chair shell unit, as shown and described.
